CLAIM

The ornamental design for a vehicle grille bar, as shown and described.

DESCRIPTION

FIG. 1 is a front perspective view of a vehicle grille bar showing a first embodiment of my new design.

FIG. 2 is a rear perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof; and,

FIG. 9 is a partial enlarged view of a portion shown in FIG. 2.

The broken line showing of portions of the vehicle grille bar form no part of the claimed design.
